DISTILLATION OF TAR

Filed April 17, 1928

UNITED STATES PATENT OFFICE

JOSEPH BECKER, OF O'HARA TOWNSHIP, ALLEGHENY COUNTY, PENNSYLVANIA, AS
SIGNOR TO THE KOPPERS COMPANY OF DELAWARE, A CORPORATION OF DELA-
WARE

DISTILLATION OF TAR

Application filed April 17, 1928. Serial No. 270,646.

My invention relates to distillation of tar, such as coal tar, water gas tar, and other analogous materials, and it has a particular relation to the manufacture of coal gas in coking retort ovens and the separation and distillation of coal tar produced therein and in other apparatus of the same or different character.

The distillation of tar in the presence of a flowing gas such as steam, flue gas, nitrogen and even air, is known and has been resorted to for the purpose of producing the decomposition or cracking of the distillates evolved, to increase the yield of such distillates and for other reasons. It is highly desirable that gas used for this purpose be inert with respect to the tar constituents and distillates, i. e., that it contain no free oxygen.

In general, prior attempts along this line have involved recirculation of the gas. In such recirculation systems, the recirculated gas must be indirectly heated, which involves certain losses and has not always accomplished the desired result in that it has been difficult to carry the distillation far enough to produce pitch residues of high melting points, especially when no other means of heating tar has been provided.

Flue gases as used in the prior art have, on the other hand, contained appreciable amounts of free oxygen, rendering them unsuitable for use without recirculation. Moreover, the flame temperatures attained when gas is used as fuel are too high to permit the products of combustion to be used for the purpose in view without deleterious effect.

It has also been proposed to employ the sensible heat of coke-oven gases leaving the distillation apparatus as a means for distilling tar, but tar distillation effected on top of or in close proximity to the coking retort ovens themselves is attended with numerous inconveniences and difficulties, as well as certain heat losses that may dissipate any advantages obtained in this manner. This is particularly true when it is attempted to obtain pitch residues from the distillation process which have very high melting points and which are suitable for coking.

An object of the present invention is to

provide a process of distilling tar that shall be free of most of the disadvantages of the prior art.

A second object of the present invention is to provide a process of distilling tar in the presence of an inert gas of suitable temperature and volume and containing substantially no free oxygen without requiring recirculation thereof.

A further object of the present invention is to provide a process of distilling tar that is adapted to the requirements of a coal-gas plant without alterations of any sort to the carbonizing structure provided in such a plant.

My invention has for further objects such other operative advantages and results as may hereinafter be found to obtain.

According to the process of my invention, I burn gaseous fuel, preferably a portion of the fuel gas to be supplied to a battery of coking retort ovens, and add further amounts of combustible gas thereto before contact with the tar to be distilled under conditions that will insure the elimination of free oxygen from the gas stream, and produce a gas of large volume and proper temperature for tar distillation.

I bring a gas mixture prepared in the manner that will be specified herein into contact with the tar to be distilled in suitable contact apparatus and preferably with counter-current flow of the tar being distilled and the gases used as distillation medium.

The gases escaping from the contact apparatus are then cooled to condense tar distillates and are used for combustion purposes for which they are suitable, for example, they may be used for heating the coking retort ovens, either alone or mixed with further fuel gas.

Preferably a portion of the fuel gas for the carbonizing apparatus is used to distill the coal tar separated from the coal gas liberated in said carbonizing apparatus but other and additional tar, such as water-gas tar or tar from other and independent carbonizing apparatus may also be distilled in the same manner and in the same distillation.

While the heat required for the distillation of the tar is preferably obtained by burning some of the coal gas produced in the coking retort ovens to which the invention is applied, it may also be obtained from other fuel gas, such as producer gas, blue gas or blast furnace gas, which is used as fuel for heating the coking retort ovens.

In order that my invention may be clearly set forth and understood, I now describe with reference to the accompanying drawing a preferred manner in which it may be practiced and embodied but without limiting my invention to this illustrative instance.

The single figure of the drawing is an elevational view, parts being shown sectionally and more or less diagrammatically of a coal gas plant and including means for distilling tar.

In this instance, coal gas is produced by the distillation of carbonaceous material such as coal in a battery of coking retort ovens 1. The gases liberated during the carbonization of the coal escape through an offtake pipe 2 into a collecting main 3 and are conveyed through a suction main 4 in which there is provided a pitch trap 5 to a primary cooler 6. The gases then pass through a further section of the suction main 4 to an exhauster 7 and are drawn into a pressure main 8, passing in succession through a tar extractor 9, an ammonia saturator 10, an acid separator 11 and a final cooler 13, which are located along the pressure main 8.

The various devices and functions performed thereby are too well known in the coal-gas art to require detailed description. Separation of tar occurs in the pitch trap 5, the primary cooler 6 and the tar extractor 9, and the tar separated in these devices is allowed to drain through lines 14, 15 and 16, respectively, into a hot drain tank 17.

The exhauster 7 may also serve to remove considerable amounts of tar and this tar is also conveyed to the hot drain tank 17. The tar collecting in the hot drain tank 17 is removed through a line 18 and passes to a separating tank 19 where any entrained ammoniacal liquor is separated therefrom.

The ammoniacal liquor escapes from the separating tank 19 through a line 20 and the tar passes through an overflow 21 into a storage tank 22 where it is held and from which it is released for distillation, as will be shown below. Additional tar from other sources may be supplied to the storage tank 22 through a line 23.

The pressure main 8 beyond the final cooler 13 divides into a branch 24 that is provided with a valve 25 and into a branch 26 leading to a fuel gas holder 27. The surplus gas not required for underfiring the coking retort ovens 1 is withdrawn through the main 24 and only the fuel gas required for underfiring the oven which may amount to from about

35 to about 40% of the total gas plus what is required for distillation of the tar is passed into the fuel gas holder 27.

The distillation of the tar is effected in a suitable contact device 30 which may be the well-known Feld scrubber or any other similar device. Tar is removed from the tank 22 through a line 31 by a pump 32. The line 31 communicates with two branches 34 and 35, having valves 37 and 38 respectively. When dehydration is not required, valve 38 is closed and valve 37 is opened and the tar passes from the line 31 through the line 34 into the upper part of the contact device 30. The tar passes downwardly through the contact device 30 in finely divided form.

The contact device 30 is provided with an adjoining furnace 40 having two main compartments 41 and 42. A portion of the fuel gas withdrawn from the fuel gas holder 27 through a main 43 is introduced through a line 44 having a valve 45 and a burner 46 into the combustion space 41 of the furnace 40.

This portion of the fuel gas is burned preferably under conditions which promote complete combustion, and the products of combustion pass into the compartment 42 where they are augmented by further amounts of gas withdrawn from the main 43 through a branch 47 having a valve 48.

Preferably enough additional gas is supplied through the main 47 to reduce the temperature of the mixed combustible gas and products of combustion to below about 1400° F. and conditions are so regulated that any appreciable amounts of free oxygen in the products of combustion of the gas burned in the compartment 41 are caused to combine with some of the unburned gas introduced to the compartment 42 through the main 47.

The mixed gas passes from the furnace 40 to the contact apparatus 30 and passes upward in counter-current to the descending tar.

During the contact of the hot gases, the tar distillation of the latter is effected and a pitch residue is removed from the bottom of the contact device 30 through a line 49 leading to a collector 50 of suitable design.

During the distillation, tar distillates are evolved and these mingle with the gaseous heating fluid and pass with it from the contact apparatus 30 through a line 51.

A cyclone separator 52 is placed in the line 51 for the purpose of removing tar entrained by the gas and of preventing such tar from being carried into the condensing apparatus. Other devices may be substituted for the cyclone separator 52, such, for example as an electrical precipitator or other device. The tar separated from the gas may be led back into the distilling apparatus.

It will be apparent that, when the distillation of tar is conducted in this manner, the gases escaping from the separating device

52 will contain tar distillates of a considerable range. For this reason, fractional condensation of these distillates is to be preferred.

In the present instance, the gases pass to a condenser 53 that is constituted of a plurality of alternate cooling sections 54 that may consist of chambers provided with a plurality of tubes wherein is circulated a cooling fluid and of fractionating sections 55 which are preferably of the well-known bell-and-tray type. The temperatures through the condenser 53 are varied according to the nature of the condensates desired but, in general, vary from a high temperature toward the bottom of the apparatus to a much lower temperature toward the top of the same. The various fractional condensates are removed from the condenser 53 through a plurality of outlets 56.

The gases leaving the condenser 53 are drawn through a line 57 through a coil 58 that is immersed in a cooling tank 59 to a receiver 60.

Water or other cooling medium is circulated through the cooling tank 59 and any condensable tar distillates not previously removed from the gas are there condensed and collect in the receiver 60. The uncon- densable gases are drawn from the receiver 60 through a line 62 by a blower 63 and pass through a line 64 to an extension of the main 43.

These gases may be admixed with further quantities of fuel gas by opening a valve 65 in the main 43 and then pass through the extension of the main 43 to fuel gas mains 85, which supply the fuel gas to the flue structure of the coking retort oven battery 1.

I may employ the tar to be distilled as a cooling medium for condensing the distillates evolved from such distillation. When this is desired, the valve 38 may be opened and the valve 37 closed. The tar from the tank 22 then passes from lines 31 and 35 into the various cooling sections 54 of the condenser 53 in series or parallel flow and is then discharged into a vapor chamber 66. As the tar flows through the cooling sections 54, it serves to condense the tar distillates from the gases passing through the condenser 53 and is thereby heated sufficiently to cause its dehydration when it is released into the vapor chamber 66.

Regulation of the condensing effect may be secured by means of fractionating valves 67 that are effective to vary the distribution of the tar through the various cooling sections 54. When the heated tar discharges through line 35 into the vapor chamber 66, the water and light oil content of the tar is released in the form of a vapor which passes through a line 68 and a coil 69 that is situated in a cooling tank 70 into a receiver 71 that may be connected through a line 72 to a fan (not shown).

The dehydrated tar collecting in the bot-

tom of the chamber 66 passes through a drain 74 into the line 34 and flows into the distillation apparatus 30.

It will be observed that the uppermost cooling section 54 of the condenser 53 is not provided with tar lines. In place of tar, water may be employed as cooling medium here, or air cooling may be sufficient.

When producer gas or other gas is to be used as fuel gas, it is supplied to the main 43 through a main 80, having a valve 81, and a valve 82 in the main 26 supplying the fuel gas holder 27 is then closed.

The actual temperatures and volumes of mixed fuel gas and products of combustion will vary somewhat according to the nature of the products obtained, i. e., whether a low yield of distillates and a soft pitch residue, or a high yield of distillates and a hard pitch residue, are to be obtained. Obviously, the amount of tar to be distilled and the time of contact of the tar with the hot gases will also affect the results.

It is preferred, however, to admix sufficient combustible gas with the products of combustion to reduce the temperature of the mixed gases to below about 1400° F. When using coal gas, which burns with a flame temperature of about 3500°-4000° F., it is found that 12 volumes of additional coal gas (at a temperature of 60° F.) are required to reduce the temperature of the mixed gases to 1400° F., for every one volume of coal gas burned.

It will be obvious that when the coking retort ovens are to be fired with gas having different flame characteristics, such for example, as producer gas, blue gas, or blast furnace gas, the proportions of the burned gas and the unburned gas required to produce a mixed gas of proper temperature will vary accordingly. However, these proportions may be precalculated with considerable accuracy.

As hereinabove set forth, it is important that the mixed gases coming into contact with the tar being distilled contain substantially no free oxygen. This requirement is easily satisfied by constructing the furnace in which the combustion and admixture takes place so that the combustible gas comes into contact with the gases of combustion at a temperature above the ignition point of the gas and any free oxygen remaining in the gases of combustion is consumed.

In addition, careful regulation of admission of air to the gas burners is desirable, and especially when producer gas or other lean gas is used, the employment of burners of the surface combustion type may be advisable. Or the combustion chamber may be constructed in such form that a "reverse flame" is obtained, i. e., air burning in an atmosphere of gas.

While formation of soot may occur when coal gas or other gas containing hydrocar-

bons such as methane and ethane is burned in this way, any soot formed will be scrubbed out of the gases by the tar being distilled and will not be introduced into flues of the coke ovens. Blue gas and producer gas contain practically no hydrocarbons, and substantially no soot will be found in their combustion.

While the mixed gases, after removal of tar distillates, contain an amount of inerts, such as nitrogen and carbon dioxide which renders them unsaleable for many purposes, the presence of these inerts is not deleterious insofar as their use as coke-oven fuel is concerned. In fact, and especially where high-chambered ovens are involved, the presence of inerts may constitute an advantage in modifying the flame characteristics of the fuel gas.

Purifications of the gas from sulphur compounds may be resorted to when necessary. Coal gas contains hydrogen sulphide, which is not in itself seriously corrosive in effect, but which is converted, upon combustion, to sulphur dioxide which is corrosive, especially when in the presence of water. Corrosion may thus be evident in the system and especially in the condensing apparatus.

To eliminate this deleterious effect, the gas to be burned may be purified from sulphur impurities, and the gas used for admixture with the products of combustion may also be purified, especially when conditions are such that some of this admixed combustible gas is burned.

It is obvious that since a portion of the fuel gas is burned for the purpose of distilling tar, the total amount of the coal gas withdrawn for fuel purposes, or the total amount of gas supplied from producers or generators, must be increased by a similar amount, in order to supply the necessary heat to the coke ovens.

While my process is particularly applicable to a coking retort oven plant, and to the employment of the gases produced therein, it is not limited in application to such use. For example, liquid fuels, such as tar and pitch, or even solid fuels, such as coal and coke, may be burned to give the heat necessary to effect the distillation of the tar, and combustible gas, for example, coal gas is then admixed with the gaseous products of combustion to reduce the temperature of the mixed gas and to insure the absence of free oxygen.

Moreover, my process is not limited to tar as such, but may be applied with equally good results to the distillation of derivatives of tar, such as tar oils, obtained by extracting or distilling the primary tar, and the term "tar" as used herein is to be construed as including such materials.

My invention is not limited to the specific examples given herein by way of example, but may be variously practiced, and is to be

construed as of the scope of the following claims.

I claim as my invention:

1. The method of carbonizing coal and obtaining pitch therefrom which comprises distilling the coal in a battery of coking retorts, removing coal gases and separating tar therefrom, burning a portion of the coal gas, adding to the products of combustion an additional quantity of the coal gas, subjecting the tar to contact with the mixture of coal gas and products of combustion whereby the tar is distilled to pitch, cooling the gases to remove tar distillates therefrom, mixing the gases used for distillation of the tar with a portion of the coal gas not so used, and employing the mixture of gases thereby obtained to heat said coking retorts.

2. The method of carbonizing coal and obtaining pitch therefrom which comprises distilling the coal in a battery of coking retorts, removing coal gases and separating tar therefrom, burning a portion of the coal gas, adding to the products of combustion an additional quantity of the coal gas, subjecting the tar to contact with the mixture of coal gas and products of combustion whereby the tar is distilled to pitch, cooling the gases to remove tar distillates therefrom and supplying the gases to said battery of coking retorts to heat the same.

3. In a method of distilling tar in which a combustible gas is employed as fuel, the steps which comprise separating a flow of said fuel gas into two streams, burning one of said streams of fuel gas, commingling the hot products of combustion thereby obtained with the other stream of fuel gas to produce a mixed gas at a temperature relatively low with respect to the temperature of said combustion and containing substantially no free oxygen, and subjecting the tar to be distilled to contact with said mixed gas.

4. In a method of distilling tar in which a combustible gas is employed as fuel, the steps which comprise separating a flow of said fuel gas into two streams, burning one of said streams of fuel gas, commingling the hot products of combustion thereby obtained with the other stream of fuel gas to produce a mixed gas at a temperature relatively low with respect to the temperature of said combustion and containing substantially no free oxygen, subjecting the tar to be distilled to contact with said mixed gas, removing said gases and cooling them to condense tar distillates thereby obtained.

5. In a method of distilling tar in which a combustible gas is employed as fuel, the steps which comprise separating a flow of said fuel gas into two streams, burning one of said streams of fuel gas, commingling the hot products of combustion thereby obtained with the other stream of fuel gas to produce

a mixed gas at a temperature of not more than about 1400° F. and containing substantially no free oxygen, and subjecting the tar to be distilled to contact with said mixed gas.

5 In testimony whereof, I have hereunto subscribed my name this 13 day of April, 1928.

JOSEPH BECKER.
